Patented Apr. 29, 1919.

Inventor:
William Weir,
Attorney.

UNITED STATES PATENT OFFICE.

WILLIAM WEIR, OF GLASGOW, SCOTLAND, ASSIGNEE TO G. & J. WEIR, LIMITED, OF GLASGOW, SCOTLAND.

FEED-WATER-HEATING APPARATUS.

1,302,257.

Specification of Letters Patent. Patented Apr. 29, 1919.

Application filed April 26, 1917. Serial No. 165,219.

To all whom it may concern:

Be it known that I, WILLIAM WEIR, a subject of the King of Great Britain and Ireland, residing at Holm Foundry, Cathcart, 5 Glasgow, Scotland, have invented certain new and useful Improvements in Feed-Water-Heating Apparatus; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

This invention relates to the treatment of feed water in systems for condensing steam and heating feed water in steamships.

The invention consists in a novel arrangement and combination of machinery and apparatus which will be described in the following specification and particularly defined in the annexed claims.

Referring to the accompanying drawing, 25 which is diagrammatic:—

a is the main condenser and *b* is a pipe which leads from the bottom thereof to the suction of a pump *c*, which will be referred to as the water-extraction pump, and which is preferably of the centrifugal type and 30 preferably located below the level of the bottom of the condenser. This pump delivers the water through a non-return valve *d* to a surface heater condenser *h* placed on the main feed pipe *f*. The water, after passing 35 through the surface heater condenser is delivered to an elevated direct-contact heater *y* where it is heated by admixture with steam, say auxiliary exhaust steam: thence the water passes to the boiler feed pump or 40 pumps *r* situated at a considerably lower level.

From the pipe *b*—or, if preferred, from the bottom of the main condenser—a pipe 45 (which is preferably given an upward turn) is led to a steam-jet air ejector *g* which is arranged to draw air and vapor from the condenser and deliver it to the before-mentioned surface heater condenser *h*. The 50 steam-jet steam, together with the water vapor brought from the condenser with the air, is condensed in this surface heater condenser, and drains into a well *k* at the bottom thereof. A pipe *m* connects this well 55 with the suction of the water-extraction

pump—or, if preferred, with the condenser—and a valve or cock *n* is provided to control the flow through this pipe. This valve or cock is itself controlled by a float *o* in the well so as to open when the water in the well 60 reaches a predetermined level.

An air discharge pipe *p* is led from a suitable part of the steam space of the surface heater condenser, or from the upper part of the well (*i. e.*, above the water level) 65 and permits of the discharge to the atmosphere of the air delivered by the air ejector.

The air ejector is arranged to deliver the air and vapor into the surface heater condenser at a pressure at or above atmosphere 70 so that the air can be discharged to the atmosphere as before mentioned. The water-extraction pump should be arranged to deliver the water at such a pressure as is required to meet the conditions of the case. 75 This pressure is generally in the neighborhood of twenty-five pounds per square inch above atmosphere.

The well or tank which is at the bottom of (or in communication with) the direct-contact heater *y*, and which receives the combined heating steam (condensed) and heated water, may be, and preferably is, provided with a float mechanism of well known or suitable type whereby, when the water in 80 said well or tank reaches a pre-determined level, a cock or valve is opened on the steam pipe to the feed pump, and the feed pump consequently started and maintained in operation until the water level again falls. 85

It is usual, in the employment of a direct-contact heater, to furnish the heater with an overflow pipe adapted—if or when the water should rise in the heater to an inconvenient height—to allow of the discharge of the excess feed water to a feed or reserve tank. Such a pipe *z* is preferably provided in the present scheme and may, if considered necessary or advantageous, be furnished with a loaded valve *s* to allow of the existence 90 within the heater of a pressure above, and also a pressure below, atmosphere. The pipe *z* conveys the excess water to the feed tank *t*. The feed tank may be connected, by a pipe *u*, 95 furnished with a hand-controlled valve *v*, with the main condenser or the suction of the water-extraction pump.

The surface heater condenser may be of any suitable surface type, that is, any suitable type in which the steam and water are 100

105

110

kept separate and the heat transferred through metal surfaces. A convenient design in the present scheme is one in which the water passes through tubes extending between two tube plates at opposite ends of a cylindrical vessel, the steam passing over the outside surfaces of the tubes. It is important to note that the water side of the surface heater condenser is subject to the pressure of discharge from the water-extraction pump while the steam side is subject to atmospheric or super-atmospheric pressure.

Under normal conditions of working the water delivered by the water-extraction pump is sufficient to condense the steam delivered from the air ejector; but, under certain conditions of working—say during maneuvering—when a reduced quantity of exhaust steam is being delivered to the main condenser while the steam-jet steam is undiminished, or not proportionately reduced, it may be necessary to supplement the condensate drawn from the main condenser and pumped through the surface heater condenser. Therefore from the pipe f between the surface heater condenser and the direct-contact feed heater a pipe w is led direct to the steam space of the main condenser, a hand-operated valve x being provided on this pipe. By means of this pipe w a sufficient circulation can be maintained through the surface heater condenser as will enable the steam from the air ejector to be condensed at a time when the main condenser is receiving no exhaust steam or insufficient steam to furnish the requisite cooling water to the surface heater condenser. In such a case the water-extraction pump is kept running, and forces water through the surface heater condenser—where it condenses the steam—and then through the pipe w to the main condenser whence it is again drawn off by the water-extraction pump and passed again to the surface heater condenser. The water in this repeated circulation is prevented from getting objectionably hot by reason of the cooling effect obtained by its passage through the main condenser.

It is to be noted that in the present scheme the feed water is circulated in a perfectly closed system, never at any time having access to the atmosphere. The air is separated from the water of condensation either before, or immediately after, leaving the main condenser; and the water thereafter is afforded no opportunity of taking up air.

Having thus described my invention, what I claim as new and desire to secure by Letters Patent is:—

1. In a steamship, in combination, a main condenser, a main feed pipe, a pump for the withdrawal of the water of condensation, *i. e.*, the feed water, from the said con-

denser, and the delivery of the same under pressure into the said main feed pipe, a surface heater condenser on the said main feed pipe, a steam-jet air ejector for the extraction of the air, with vapor, from the said condenser and the delivery of the same into the said surface heater condenser, the said surface heater condenser being arranged for the heating of the feed water by the condensation of the steam from the ejector, means for returning this condensed steam to the suction of the said pump, an elevated direct-contact heater on the main feed pipe beyond the said surface heater condenser and arranged for the further heating of the feed water by admixture with steam, a return pipe connecting the main condenser with the main feed pipe at a point between the surface heater condenser and the direct-contact heater, and a hand-controlled valve on the said return pipe.

2. In a steamship, in combination, a main condenser, a main feed pipe, a pump for the withdrawal of the water of condensation, *i. e.*, the feed water, from the said condenser, and the delivery of the same under pressure into the said main feed pipe, a surface heater condenser on the said main feed pipe of which the water side is under the pressure of discharge from the said pump while the steam side is under a pressure not less than atmospheric, a steam-jet air ejector for the extraction of the air, with vapor, from the said condenser and the delivery of the same into the said surface heater condenser, the said surface heater condenser being arranged for the heating of the feed water by the condensation of the steam from the ejector, means for returning this condensed steam to the suction of the said pump, an elevated direct-contact heater on the main feed pipe beyond the said surface heater condenser and arranged for the further heating of the feed water by admixture with steam, a return pipe connecting the main condenser with the main feed pipe at a point between the surface heater condenser and the direct-contact heater, and a hand-controlled valve on the said return pipe.

3. In a steamship, in combination, a main condenser, a main feed pipe, a pump for the withdrawal of the water of condensation, *i. e.*, the feed water, from the said condenser, and the delivery of the same under pressure into the said main feed pipe, a surface heater condenser on the said main feed pipe, a steam-jet air ejector for the extraction of the air, with vapor, from the said condenser and the delivery of the same into the said surface heater condenser, the said surface heater condenser being arranged for the heating of the feed water by the condensation of the steam from the ejector, a well at the bottom of the said surface heater condenser, a pipe connection from this well

to the suction of the said pump, an elevated direct-contact heater on the main feed pipe beyond the said surface heater condenser and arranged for the further heating of the feed water by admixture with steam, a return pipe connecting the main condenser with the main feed pipe at a point between the surface heater condenser and the direct-contact heater, and a hand-controlled valve 10 on the said return pipe.

4. In a steamship, in combination, a main condenser, a main feed pipe, a pump for the withdrawal of the water of condensation, *i. e.*, the feed water, from the said condenser, and the delivery of the same under pressure into the said main feed pipe, a surface heater condenser on the said main feed pipe, a steam-jet air ejector for the extraction of the air, with vapor, from the 15 said condenser and the delivery of the same 20 into the said surface heater condenser, the

said surface heater condenser being arranged for the heating of the feed water by the condensation of the steam from the ejector, means for returning this condensed 25 steam to the suction of the said pump, an elevated direct-contact heater on the main feed pipe beyond the said surface heater condenser and arranged for the further heating of the feed water by admixture with 30 steam, a feed tank, a pipe connecting the said direct-contact heater with the said feed tank, a pipe connecting the said feed tank with the suction of the said pump, a pipe connecting the main condenser with the 35 main feed pipe at a point between the surface heater condenser and the direct-contact heater, and hand-controlled valves on the last two mentioned pipes.

I hereby sign my name to this specification.

WILLIAM WEIR.
